SIFTER BOX AND SIFTER UNIT THEREFOR

Robert L. Hoffman, Tuckahoe, N.Y., assignor to Cross Paper Products Corp., New York, N.Y., a corporation of New York

Application July 14, 1958, Serial No. 748,296

8 Claims. (Cl. 222—555)

This invention relates to a sifter box and sifter unit therefor. One object of this invention is to generally improve the construction shown in United States Patent No. 2,480,096.

A further object of this invention is to provide in a device of the character described, a highly improved sifter unit comprised of three sheets or layers of superimposed cardboard attached together, the top cardboard layer having a central circular opening, the middle cardboard layer having a central circular opening larger than the opening in the top cardboard layer, and the bottom cardboard layer having a small opening eccentric with respect to the first two mentioned openings, and a circular valve disk rotatable in the opening of the middle cardboard layer and being disposed between the top and bottom cardboard layers, and being formed with a plurality of small outlet openings adapted to register with the opening in the bottom cardboard layer, in one angular position of the valve disk.

Another object of this invention is to provide in a sifter unit of the character described, a paper sheet attached to the top surface of the bottom cardboard layer and on which the rotary valve disk lies, said paper sheet being formed with an opening registering with the opening in the bottom cardboard layer.

Another object of this invention is to provide a highly improved sifter box of the character described, said sifter comprising a sifter unit fitted within one end of a tube and engaging an inwardly rolled end edge of said tube, and said sifter unit being held in place against the rolled end edge of said tube by an inner tube telescoped within the first tube and having an end edge contacting the underside of the sifter unit.

Yet another object of this invention is to provide a sifter unit of the character described, which is oval in shape and in which the circular opening is centrally located, and in which the valve disk is formed with a diametric ridge projecting upwardly through the opening in the top cardboard layer so that it may be engaged by the fingers for rotating the disk.

Yet another object of this invention is to provide a strong, rugged and durable sifter box construction and sifter unit therefor, which shall be relatively inexpensive to manufacture and yet practical and efficient to a high degree and use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a front elevational view of a sifter box embodying the invention,

Fig. 2 is a top plan view thereof,

2

Fig. 3 is a cross-sectional view taken along line 3—3 of Fig. 2.

Fig. 4 is a cross-sectional view taken along line 4—4 of Fig. 3.

5 Fig. 5 is a cross-sectional view taken along line 5—5 of Fig. 1, and

Fig. 6 is a partial view similar to Fig. 3, but showing the valve disk in a different angular position.

Referring now in detail to the drawing, 10 designates 10 a sifter box embodying the invention. The same comprises an outer case 11. Said case 11 comprises an outer case wall 12 of oval transverse cross-section having an inwardly rolled lower edge flange 13 and an upper end edge 14. Mounted within the case wall 12, and resting on the lower end edge 13, is a bottom wall 15 which may be press-fitted in place or glued, as desired.

Slidable within the outer case 11 is an inner case 16. The inner case 16 comprises an outer tubular wall 17, likewise of oval cross-section and telescoped within the 20 tubular wall 12. Wall 17 has a lower end edge 18 resting on the bottom wall 15. Wall 17 has an upper inwardly rolled end edge flange 19 spaced above the upper edge 14 of wall 12. Telescoped within wall 17 is a wall 20, likewise of oval cross-section. Wall 20 has a 25 lower end edge 21 likewise resting on the upper surface of the bottom wall 15. The upper end 22 of wall 20 is spaced below the upper inwardly rolled edge 19 of tubular wall 17.

Mounted within the upper end of the wall 17, and 30 between the upper edge 22 of wall 20 and the inwardly rolled edge 19 of wall 17, is a sifter unit 25. Said sifter unit 25 comprises a bottom cardboard layer 26, a top cardboard layer 27 and a middle or intermediate cardboard layer 28. These are superimposed and have similar outer outlines. They have oval-shaped outer peripheries contacting the inner surface of wall 17. The top layer 27 is formed with a central cut-out opening 27a. The intermediate layer 28 is formed with a central cut-out opening 28a larger than the opening 27a. The bottom layer 26 is formed with an eccentric smaller cut-out or opening 26a, offset from the center of the openings 27a and 28a. Glued, or otherwise adhered to the upper surface of the bottom cardboard layer 26, is a thin sheet 30 formed with an opening 30a registering with the opening 26a. Rotatively mounted on the paper sheet 30, 40 and between the said paper sheet and the upper cardboard layer 27, is a rotary valve disk member 31 which may be made of synthetic plastic material. The inner periphery of opening 27a of top layer 27 overlaps the outer periphery of the disk 31. The disk 31 substantially has the same thickness as the intermediate layer 28. Said disk 31 is formed with a central transvers diametric upwardly extending ridge 32 projecting through the opening 27a. The ridge 32 may be grasped by the fingers of the operator for rotating the disk.

50 Said disk 31 is formed with a plurality of small spaced openings 33. Four such openings 33 are shown in the drawing, although any suitable number may be provided. All of the openings 33 are, however, within a circular outline having diameter equal to the diameter of the opening 26a.

In the closed position of the box shown in Figs. 2, 3 and 5, the openings 33 are offset from the openings 30a and 26a so that powder material within the box cannot be sifted through. However, upon rotating the disk 30 to the position shown in Fig. 6, the openings 60 33 are brought into registry with the openings 26a and 30a, so that the powder material may be sifted out of the box.

A cover 40 is provided for the box. Said cover 40 comprises an outer oval-shaped tubular wall 41 of the 70 same dimension as the tubular wall 12. The wall 41

may be telescoped onto the upper end of the wall 17. Wall 41 has a lower edge 42 which contacts the upper edge 14 of wall 12. The upper edge of wall 41 is inwardly rolled, as at 42, and frictionally fitted within said wall 41, and contacting the underside of the rear edge 42 is a top cover disk 44 which is disposed above the inwardly rolled edge 19 when the cover is fully mounted on the box, with the edges 14 and 42 mutually contacting.

The top cardboard layer 27 is glued to the intermediate cardboard layer 28, which in turn is glued to the paper sheet 30, which as stated before is glued to the bottom cardboard layer 26. It will now be observed that the cardboard layers, paper sheet and valve disk 31 form a unit which may be prefabricated and assembled with the sifter box.

It will thus be seen that there is provided an apparatus in which the several objects of this invention are achieved and which is well adapted to meet the condition of practical use.

As possible embodiments might be made of the above invention, and as various changes might be made in the embodiment above set forth, it is to be understood that all matter herein set forth or shown in the accompanying drawings is to be interpreted as illustrative and not in a limiting sense.

I claim:

1. A sifter box having a sifter unit comprising a flat bottom cardboard layer, a flat intermediate cardboard layer and a flat top cardboard layer, all superimposed and having outer registering peripheries, the intermediate layer being formed with a central circular opening, the top cardboard layer being formed with a central circular opening smaller than the first-mentioned circular opening, the bottom cardboard layer being formed with a smaller opening eccentric with respect to the first mentioned openings, a valve disk rotatably mounted between the top and bottom cardboard layers and being disposed in the plane of the intermediate cardboard layer, said disk being formed with a plurality of spaced openings eccentric with respect to the disk, and adapted in one angular position of the disk, to register with the opening in the bottom cardboard layer, said box comprising a first tube having an inwardly extending annular lower end flange, a bottom wall fitted within the first tube and resting on said lower end flange, a second tube telescoped within said first tube and having a lower end resting on the bottom wall, and an upper inwardly extending flange, a third tube telescoped within the second tube and having a lower end resting on said bottom wall, said third tube having an upper rim on which the bottom cardboard layer seats, and said second tube having a top annular flange engaging over the rim of the top cardboard layer clampingly securing said top, intermediate and bottom layers and hence said disk in related assembly with said box.

2. The combination of claim 1, in combination with a paper sheet glued to the upper surface of the bottom cardboard layer, and being interposed between the middle cardboard layer and the bottom cardboard layer, and said valve disk lying on said paper sheet.

3. The combination of claim 2, said cardboard layers and paper sheet being glued together whereby said cardboard layers, sheet and valve disk form a unit.

4. A sifter box comprising a first tube having an inwardly rolled lower end edge, a bottom wall fitted within said first tube and resting on said lower end edge, a second tube telescoped within the first tube and having a lower end edge resting on the bottom wall, and an upper inwardly rolled end edge spaced above the upper edge of the first tube, a third tube telescoped within the second tube and having a lower end edge contacting the upper surface of the bottom wall, said third tube having an upper edge spaced below the inwardly rolled upper end edge of the second tube, a sifter unit fitted within the

upper end of the second tube and between the upper inwardly rolled end edge of the second tube and the upper end edge of the third tube, said sifter unit comprising a bottom cardboard layer, an intermediate cardboard layer and a top cardboard layer, the top cardboard layer being formed with an opening, the intermediate cardboard layer being formed with an opening concentric with the first opening and of larger diameter, and the bottom cardboard layer being formed with an opening eccentric with respect to the first two openings but lying within the periphery of the first opening, and a valve disk rotatably mounted between the top and bottom cardboard layers, the top cardboard layer overlapping the outer periphery of the disk, and said disk being formed with a plurality of outlet openings adapted in one angular position of the disk to register with the opening in the bottom cardboard layer.

5. The combination of claim 4, in combination with a paper sheet glued to the upper surface of the bottom cardboard layer and being located between the bottom and intermediate cardboard layers, and said valve disk lying on said paper sheet, said paper sheet having an opening registering with the opening in the bottom cardboard layer, and said cardboard layers and sheet being glued together to form a unit which may be prefabricated with the valve disk before assembling with said tubular members.

6. The combination of claim 5, in combination with a cover telescoped on the upper end of the second tube and having an inwardly rolled upper end edge and a top wall fitted within the cover and contacting the underside of the inwardly rolled upper end edge of said cover.

7. A sifter box having a sifter unit comprising a flat bottom cardboard layer, a flat intermediate cardboard layer and a flat top cardboard layer, all superimposed and having outer registering peripheral edges, the intermediate layer being formed with a central circular opening, the top cardboard layer being formed with a central circular opening smaller than the first-mentioned circular opening, the bottom cardboard layer being formed with a smaller opening eccentric with respect to the first-mentioned openings, a valve disk rotatably mounted between the top and bottom cardboard layers and being disposed in the plane of the intermediate cardboard layer, said disk being formed with a plurality of spaced openings eccentric with respect to the disk, and adapted in one angular position of the disk, to register with the opening in the bottom cardboard layer, said box including a first tube having an inwardly extending annular lower end flange, a bottom wall fitted within the first tube and resting on said lower end flange, a second tube telescoped within said first tube and having a lower end resting on the bottom wall, a third tube telescoped within the second tube and having a lower end resting on said bottom wall, said third tube having an interior seat upon which said bottom cardboard layer rests, said second tube having a portion surrounding said registering peripheral edges and a portion overlying the rim of said top cardboard layer clampingly securing said unit against said seat.

8. A sifter box having a sifter unit comprising a flat bottom cardboard layer, a flat intermediate cardboard layer and a flat top cardboard layer, all superimposed and having outer registering peripheral edges, the intermediate layer being formed with a central circular opening, the top cardboard layer being formed with a central circular opening smaller than the first-mentioned circular opening, the bottom cardboard layer being formed with a smaller opening eccentric with respect to the first-mentioned openings, a valve disk rotatably mounted between the top and bottom cardboard layers and being disposed in the plane of the intermediate cardboard layer, said disk being formed with a plurality of spaced openings eccentric with respect to the disk, and adapted in one an-

gular position of the disk, to register with the opening in the bottom cardboard layer, said box comprising a first tube, a second tube within the first tube, and a third tube within the second tube, a bottom wall, means at the lower ends of the first tube to clamp the bottom wall to the lower ends of the second and third tubes, said second tube receiving and surrounding said registering edges, and means on the second tube to clamp the sifter to the upper edge of the third tube.
